UNITED STATES PATENT OFFICE.

JIM O. TURVAN, OF FORT GRIFFIN, TEXAS.

AUTOMATIC RAILWAY-GATE.

1,182,332.

Specification of Letters Patent.

Patented May 9, 1916.

Application filed April 6, 1915. Serial No. 19,528.

To all whom it may concern:

Be it known that I, JIM O. TURVAN, citizen of the United States, residing at Fort Griffin, in the county of Shackelford and 5 State of Texas, have invented certain new and useful Improvements in Automatic Railway-Gates, of which the following is a specification.

This invention relates to new and useful 10 improvements in railway gates.

The object of the invention is to provide a swinging gate and automatic means of particular construction for operating the gate; said means including a rail arranged 15 to be depressed by the engine and so held while the train is passing whereby the gate is elevated.

Another object of the invention is to provide a device of the character described that 20 will be strong, durable, efficient, easy of operation, and simple and comparatively inexpensive to construct, also one in which the several parts will not be likely to get out of working order.

25 With the above and other objects in view the invention has relation to certain novel features of construction and operation, an example of which is described in the following specification and illustrated in the accompanying drawings, wherein:

Figure 1 is a perspective view of the invention and a portion of a railway track, the open position of the gate being indicated in dotted lines, and Fig. 2 is a cross-sectional 35 detail of the tripping rail and component parts.

In the drawings the numeral 1 designates 40 an elongated cross tie on which the gate is mounted. A post 2 is secured to each side of the tie and carries a trunnion 3 at its upper end on which a gate 4 is pivoted. The gate normally projects horizontally across the track at substantially right angles to the rails A and B and rests in a seat 5 projecting 45 from a latch post 6.

Along the inner side of the rail A a tripping rail 7 is disposed and extends a considerable distance on each side of the gate. The ends of the rail 7 are inclined downward at each end and terminate in depending lugs 8 slotted to receive pins 9 which limit the upward and downward movements of said rail. At intervals angular guides 10 are engaged under the rail A and receive the tripping rail as shown. Opposite each 55 guide a filler block 11 is fitted under the

head of the rail A and against the web and has its outer face flush with the side of the rail head. By this construction the tripping rail is prevented from tilting laterally 60 and is given a free channel in which to work.

At the end of the tie 1 adjacent the rail A a lever 12 has its end pivoted on the side of said tie and extends under the rails to a point beyond the post 2 where it is pivoted 65 to the lower end of a link 13. The link has its upper end pivoted to the gate, eccentrically with relation to the trunnion 3. It is obvious that the lever when depressed or swung downward will pull down on the link 70 which will exert this force on the gate, where the latter will be swung upward or elevated as shown in dotted lines in Fig. 1. The gate is not swung to a true perpendicular position but arrested at a slight angle. 75 The pivoted end of the gate is rounded to facilitate swinging as shown.

At the end of the tie adjacent the post 2 an upright 17 is disposed at an angle so as to incline toward the gate and is held by a 80 pair of braces 18 which are also secured to the tie. The rounded end of the gate extends between these braces which act to steady it in its operation. At the upper end of the upright a plunger 20 is mounted and 85 normally extended by a spring 19 coiled thereabout between the upright and the head of the plunger. When the gate is elevated a notch 21 engages the head of the plunger and forces the same back or into 90 the upright, thus cushioning the elevation of the gate and tending to force the gate downward when released.

Over the lever 12 the tripping rail 7 carries a depending shoe 15 which rests on a 95 boss extending upward from the lever. When the rail is depressed the shoe rides on the boss and swings the lever downward as indicated in dotted lines in Fig. 1. Thus when the engine of a train approaching in 100 either direction nears the gate, the flanges of the wheels ride onto the rail 7 and depress the same, whereby the gate is elevated as described. The rail 7 is long enough to operate the gate in advance of the 105 train and to hold it elevated until the rear extremity has passed. When pressure on the rail 7 is relieved the gate by its own weight and the pressure of the plunger 20 will swing down thus restoring the parts to 110 their normal position.

The operating parts are few in number and

of simple construction. The invention is presented as including all modifications and changes as come within the scope of the appended claim.

5 What I claim, is:

In a railway gate structure, the combination of an elongated base, a pair of posts having their lower ends secured to the sides of the base, a gate normally overhanging the base and having one end pivotally mounted between the upper end of the posts, a depressible lever disposed along one side of the base and having its swinging end projecting past the posts, a depressible tripping rail disposed over and resting on the lever adjacent the pivot point of the latter, a vertical link pivoted at its lower end to the swinging end of the lever and having its up-

per end pivoted to the gate above the pivot point of the latter, an upright mounted on the base and inclined toward the pivoted end of the gate, a pair of braces extending from the base to the upright and between which the pivoted end of the gate projects, and a spring pressed plunger mounted on the upright and inclined toward the gate, said gate having a seat positioned to receive the free end of the plunger when the gate is swung upward by the lever and link.

In testimony whereof I affix my signature in presence of two witnesses.

JIM O. TURVAN.
